UNITED STATES PATENT OFFICE

CHARLES H. MUCKENHIRN, OF DETROIT, MICHIGAN

DESIGN FOR A COMBINATION OF AUTOMOBILE RADIATOR, LAMPS, AND FENDERS

Application filed May 10, 1929. Serial No. 31,170. Term of patent 7 years.

To all whom it may concern:

Be it known that I, CHARLES H. MUCKENHIRN, a citizen of the United States, residing at 1923 Ford Building, Detroit, in the county of Wayne and State of Michigan, have invented a new, original, and ornamental Design for a Combination of Automobile Radiator, Lamps, and Fenders, of which the following is a specification, reference being had to the accompanying drawings forming part thereof.

Figure 1 is a front elevational view of a combination of automobile radiator, lamps, and fenders, showing my new design; and

Figure 2 is a diagrammatic plan view thereof.

I claim:

The ornamental design for a combination of automobile radiator, lamps, and fenders, substantially as shown.

CHARLES H. MUCKENHIRN.
